UNITED STATES PATENT OFFICE.

HOLLIS W. MOORE, OF OLEAN, NEW YORK.

STEAM-BOILER.

SPECIFICATION forming part of Letters Patent No. 391,265, dated October 16, 1888.

Application filed April 19, 1888. Serial No. 271,168. (No model.)

To all whom it may concern:

Be it known that I, HOLLIS W. MOORE, a citizen of the United States, and a resident of Olean, in the county of Cattaraugus and State of New York, have invented certain new and useful Improvements in Steam-Boilers and Generators; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of my boiler, and is a vertical section. Fig. 2 is a transverse vertical section thereof. Fig. 3 shows the ratchet-shaped diaphragm, and Fig. 4 shows the metal plugs H.

20 The invention relates to improvements in steam boilers or generators; and it consists in the construction and novel combination of parts, as hereinafter set forth.

The object of the invention is to provide a 25 steam-generator which can be manipulated at small cost, and is of compact form; and, further, to provide a boiler of great strength, rendering it comparatively safe from explosion; and also, its construction is such that the expansion or contraction of its different parts are 30 harmless to each other.

Referring to the drawings, A designates the vertical portion of the boiler, which consists of the several sections a, b, c, d, e, f, and g. 35 Each section consists of the three or more short vertical tubes h, joined together by the transverse tubular sections i, so that the several sections communicate when placed one upon the other, as shown.

40 The tubes h of the sections a and g are provided at their outer ends with a plate-piece, j, having a central opening, through which the rods k pass. A head, a', is secured to the rod k, near the lower end, and the upper threaded end of each rod is engaged by a nut, b'. As the rods k pass through the tubes h, the several sections are held firmly together by turning the nut tightly on each rod.

The tubes h of the sections a, c, and e are 45 provided with hollow threaded bosses c', and similar bosses, d', communicate with the transverse tubes of the same sections. The bosses

are omitted from the outer tubes, h, of the sections b and d, so that the said bosses are alternately odd and even, which brings the bottom 55 of each horizontal tube B in line with the heat from the fire.

The outer tubes, h, of the two lower sections, f and g, are provided with the hollow bosses, and the intermediate ones are omitted, thus 6c leaving a space for the grate C and the fuel. The horizontal tubes B have the threaded end m, which engages the internal thread of the bosses, and a threaded cap or plug, n, closes the outer end of each tube B. 65

D designates the feed-water pipe, which enters one of the lower tubes B, and gage-cocks E communicate, respectively, with the sections a, b, and c. By means of the cocks E the water may be regulated so that the upper 70 tiers of tubes may be used as a steam-chamber, and a steam-pipe, g', may lead from one of said tubes. If desired, however, the steam-drum F may be connected to the steam-pipe, and in that event the several tubes may be 75 filled with water.

G represents a ratchet-shaped diaphragm placed centrally and longitudinally within each tube B, designed to produce and maintain a current of water. 8c

H shows metal plugs having a threaded portion to engage threaded openings through the wall of the tubes B.

The inner end of each plug H is provided with a transverse conical opening, o, the larger 85 end of the opening facing the vertical portion of the generator. These openings being conical and placed in the position described, give a positive and constant current to the water of considerable velocity. 90

It is obvious that either the diaphragm or the plugs may be omitted from the tubes, as one may act independently of the other; but I prefer to employ the devices jointly for breaking or separating the water within the tubes. 95

The generator above described may be inclosed in a suitable casing, J, having a smoke-outlet, K, through its top and provided with a fire and ash door.

Having described my invention, what I claim 100 is—

1. The vertical portion consisting of sections bolted together and having the transverse connecting-tubes and the hollow thread-

ed bosses, the tubes B, having the closed outer ends, and the grate, substantially as specified.

2. The combination of the sections consisting of the tubes *h*, the transverse connecting-tubes, and the internally-threaded hollow bosses, the rods having the headed end and the threaded end, the nut thereon, the plates *j*, having the opening for the rod, the horizontal tubes closed at their outer end and 10 the opposite end engaging the bosses, the grate, the water-feed pipe, and the steam-pipe, substantially as specified.

3. In a boiler, the combination, with the tubes, of the ratchet-shaped diaphragm, substantially as specified.

4. In a boiler or steam-generator, in combination with the tubes, the plugs provided with

the transverse conical opening, the larger end facing the vertical portion of the generator, substantially as specified.

20

5. In combination with the horizontal tubes of a boiler, the longitudinal ratchet-shaped diaphragm and the plugs having the threaded portion to engage threaded openings through the wall of the tube, and having the end within 25 the tube provided with the conical opening, substantially as specified.

In testimony whereof I affix my signature in presence of two witnesses.

HOLLIS W. MOORE.
